Certificate of Correction.

It is hereby certified that the assignee in Design Letters Patent No. 58,826, granted August 30, 1921, upon the application of Homer J. Richards, of Carrollton, Ohio, for a Design for a "Tire-Tread," was erroneously described and specified as "The L. & M. Rubber Company," whereas said assignee should have been described and specified as *The Tuscan Tire & Rubber Company*, as shown by the records of assignments in this office; and that the said Letters Patent should be read with this correction therein that the same may conform to the record of the case in the Patent Office.

Signed and sealed this 11th day of September, A. D., 1923.

Specification for Design.

Patented Aug. 30, 1921.

Application filed March 23, 1920. Serial No. 368,149. Term of patent 7 years.

To all whom it may concern:

Be it known that I, HOMER J. RICHARDS, a citizen of the United States, residing at Carrollton, in the county of Carroll and State of Ohio, have invented a new, original, and ornamental Design for a Tire-Tread, of which the following is a specification, reference being had to the accompanying drawing, forming part hereof.

The figure is a perspective view of a tire tread showing my new design.

I claim:

The ornamental design for a tire tread substantially as shown.
